United States Patent Office

Des. 231,094
Patented Apr. 2, 1974

231,094

SUPersonic AIRPLANE

Gerald F. Schmidt, Wichita, Kans., assignor to The
Boeing Company, Seattle, Wash.

Filed Oct. 20, 1971, Ser. No. 190,849

Term of patent 14 years

Int. Cl. D12—07

U.S. Cl. D12—78

Fig. 1

Fig. 2

FIG. 1 is an upper perspective view of a supersonic airplane showing my new design;

FIG. 2 is a bottom perspective view;

FIG. 3 is a top plan view;

FIG. 4 is a side elevational view;

FIG. 5 is a front elevational view; and

FIG. 6 is a cross sectional view taken at the section indicated by line 6-6 of FIG. 4.

The broken line disclosure of landing gears is for illustrative purposes only.

I claim:

The ornamental design for a supersonic airplane, as shown and described.
